UNITED STATES PATENT OFFICE.

AUSTIN D. BRIXKEY, OF NEW YORK, N. Y., ASSIGNOR TO ORDINATOR COMPANY, INC.,
A CORPORATION OF NEW YORK.

ADJUSTABLE SHADE SUPPORT.

Application filed May 25, 1917, Serial No. 170,817. Renewed October 30, 1922. Serial No. 598,016.

To all whom it may concern:

Be it known that I, AUSTIN D. BRIXKEY, a citizen of the United States, residing at city, county, and State of New York, have invented 5
new and useful Improvements in Adjustable Shade Supports, of which the following is a specification.

This invention relates to shade roller supports and securing means, and particularly 10 to structures wherein the shade roller is adjustably mounted.

The present invention is an improvement upon the structures of my application Serial 15 No. 66,256, filed December 11th, 1915.

One object of the invention is to so construct the shade roller supporting brackets as to relieve them of binding in their guides under the stress of pull on the supporting 20 cord or weight of the roller, shade, etc., thereby contributing to the smoothness and ease of operation.

A further object of the invention is to provide an arrangement and construction of 25 cord guides and holders such that the shade may be readily adjusted to cover any desired area at any desired portion of the window.

A further object of the invention is to provide an apparatus wherein, if one end of 30 the shade roller falls, it will not come against the window frame so as to pry on the bracket and strain or perhaps break it, while at the same time preventing a toggle joint action operated on by the weight of the shade, roller, etc., tending to jam and bind the bracket in its guide or perhaps break it.

Another object of the invention is to provide means for reducing the noise and shock 35 to the parts when the bracket comes to the end of its guide as when the bracket falls or is lowered rapidly.

Other and ancillary objects of the invention will appear hereinafter.

In the accompanying drawings, which 40 illustrate the invention—

Figure 1 is a front elevation of a window equipped with the invention;

Figure 2 is a section through the shade roller pintle and cord, on the line 2—2 of Figure 1, this figure being on an enlarged 45 scale and the lower part of the apparatus being broken away;

Figure 3 is a similar view of the apparatus at the other end of the shade roller, being an enlarged and partly broken away section 50 on the line 3—3 of Figure 1;

Figure 4 is an elevation of the shade supporting bracket shown in Figure 2 viewed from the opposite side from that shown in the latter figure;

Figure 5 is an elevation of the apparatus 60 of Figure 4 viewed from the right of that figure;

Figure 6 is an elevation of the shade supporting bracket shown in Figure 3 viewed from the opposite side from that shown in 65 the latter figure;

Figure 7 is an elevation of the apparatus of Figure 4 viewed from the left of that figure;

Figure 8 is a view similar to Figure 1 of 70 the upper portion of the window, partly broken away and on an enlarged scale;

Figure 9 is a top plan view of the apparatus viewed from the line 9—9 of Figure 8, the window frame being in section and the 75 upper portion as well as the cords being removed;

Figure 10 is an elevation of a stop in the 80 end of the bracket guide, the guide being partially shown in section;

Figure 11 is an elevation of a cord holder;

Figure 12 is an end view of the holder of 85 Figure 11 showing the manner of securing it to a shade stick which is shown in section;

Figure 13 is a view similar to Figure 8 showing the bracket guides, etc., secured to the outside of the window frame instead of the inside as shown in Figures 1 and 8.

Figure 14 is a top plan view of the apparatus of Figure 13 as viewed from the line 90 14—14, the window frame being in section and the upper portion as well as the cords being removed;

Figure 15 is a front elevation, partly in 95 section and on an enlarged scale, of the upper end of the left hand bracket guide and the cord guide at the top thereof, of the apparatus of Figures 13 and 14;

Figure 16 is a front elevation on an enlarged 100 scale of the bracket for the central cord guide as shown in Figure 13; and

Figure 17 is an end view of the device of Figure 16.

Referring to the drawings, and first to 105 Figures 1 to 12 inclusive, the apparatus comprises a window frame A, a shade roller B supported in adjustable brackets C and D and carrying the shade E. The brackets C and D are guided by the respective bracket 110

guides F and G secured to opposite sides of the window frame, while the supporting cords H and I pass over guides K and L at the corners of the frame and at the tops of 5 the bracket guides. The cords then pass over the guides M, secured to the top of the window frame at substantially its middle point whence they pass downwardly behind the shade, merging into a single cord N 10 which passes through a cord stop O, and thence to a cord stop P secured to the shade at substantially its middle point.

The bracket C comprises a plate 1 on which are rotatably mounted wheels 2 and 15 3. These wheels are beveled at their peripheries as shown, so as to closely fit within the grooves 4 and 5 in the guides C as shown most clearly in Fig. 9. The wheels may be made from celluloid which provides 20 an efficient, durable and non-sonorous structure. From the front of the plate 1 extends an arm 6, which is offset downwardly, as shown in Figs. 2 and 4 and is also offset laterally as shown in Figs. 5 and 9 so as to 25 bring the point of support of the shade roller more nearly in the plane of the bracket wheels. At the lower end of the arm 6 is pivoted a pintle-supporting arm 7, having a recess 8 into which projects the 30 usual squared pintle 9 of a Hartshorn type of shade roller, which is fixed therein by means of a set screw 10. The top of the bracket is cut away at 11 to form clearance for the knot 12 tied in the end of the cord 35 H, just below the opening 13 in the offset ear 14 of the body 1. This forms the connection of the lifting cord with the bracket as the knot 12 cannot pass through the hole 13, it being observed that the ear is offset in 40 the direction of the plane of the bracket wheels.

The offsetting of the cord connection and the shade support toward the plane of the bracket wheels reduces the tendency to twist 45 the wheels in the guide by pull upon the cord or the bearing down of the weight of the roller, shade, etc., so that binding of the wheels in the guide is lessened and the ease of operation enhanced.

The other bracket D comprises a plate 15 in which are rotatably mounted wheels 16 and 17 of celluloid which enter within the guide G, the peripheries of the wheels being beveled and fitting snugly in grooves 18 55 and 19 of the guide in a manner as already referred to in connection with the rollers of the other bracket C. There is also a forwardly projecting arm 20 from the plate 15 and, like the arm 6 of the bracket C, it is 60 offset laterally for a purpose as referred to in connection with the other bracket. Instead of being offset downwardly, however, the arm 20 is offset upwardly and at its upper end has pivoted a depending arm 21 for 65 engaging with and supporting the shade

roller pintle. This arm 21 has a channel 22 adapted to receive the ball and having a bed 23 therefor at its lower end. At the edge or mouth of the channel are ledges or flanges 24, which prevent the passage of a ball fitting within the channel. At the upper end of the channel, however, the ledges are cut away to form an opening 25 through which the ball can be removed. The pintle of the shade roller, corresponding to the usual 70 Hartshorn roller of round section so as to permit rotation, comprises a neck 26 secured at one end to the shade roller and at the other end carries the ball 27 adapted to be entered through the opening 25 to the channel 22 whence it gravitates to the bottom thereof, finding in its lower end a bed so that the pintle is secured to the bracket by a universal joint.

In installing the shade roller, the squared 85 pintle is secured in the bracket C as described. If in entering the other pintle in the bracket D the end of the roller is accidentally dropped, the pivoted arm 7, being 90 upstanding from its pivot, will swing the roller end away from the window frame so that the roller will clear the frame in swinging into a vertical position so that the prying upon the bracket which would take 95 place if the roller came against the frame before this position was reached, is avoided. At the other bracket, however, the pintle having a movable connection with its pivoted supporting arm, if the arm were upstanding a toggle would be formed by the 100 roller and the pivoted arm supporting the pintle whenever the angle between the axis of the roller and the arm was greater than a right angle, and this toggle would tend to be straightened by the weight of the roller and supported parts, this force being much magnified in its application to the bracket by the toggle so that a considerable force is 105 exerted thereon, tending to bind the bracket in its guides and perhaps break some of the parts. By making the pivoted pintle supporting arm depending this difficulty is avoided and furthermore the movable connection of the pintle with its supporting 110 arm is more satisfactorily accomplished and 115 by a simpler structure.

Secured to an ear 28 substantially as described in connection with the bracket D, is a supporting cord I having the knot 28' at 120 its end. The bracket K is secured to the frame at its corner above the bracket guide F and comprises a frame 29 in which is pivoted a pulley 30 acting as a guide for the cord H. Similarly the bracket L, comprising a frame 31 in which is mounted a rotatable pulley 32, acts as a guide for the cord I at the upper end of the bracket guide C. The guide M comprises the frame 33 in which are rotatably mounted pulleys 34 and 35 respectively receiving and guiding the 125 130

cords H and I. As already referred to, this guide is secured to the frame at substantially its middle point. The combination of this mounting of cords with the wheeled 5 brackets moving in grooved guides is a particularly efficient apparatus. The wheels running in the grooves give an easily and smoothly operated structure provided they are not bound or twisted in the guides. 10 With the arrangement of cords heretofore employed with such brackets, the brackets were connected to different length of cord so that with the inevitable stretching by use, the cords were soon of different relative 15 lengths causing tilting of the roller and binding of the wheels in the grooves. By the arrangement of cord mounting as described this disadvantage is avoided and furthermore, the placing of the guides for 20 the bracket cords at the centre of the top of the window frame facilitates its co-operation with the holder on the window sill to which the shade cord extends.

At the bottom of each of the bracket 25 guides is a closure comprising a plug 36 closely fitted within the channel of the guide and a rounded cap 37 which fits over the end of the channel. This closure is secured in place by a screw 38 which secures the plug 30 to the guide or may pass through the guide into the window frame. To relieve the impact of the bracket in coming against the closure, as when the bracket falls or otherwise, a rubber buffer 39 is mounted in a 35 socket in the upper end of the plug 36.

In securing the bracket guides to the window frame, screws may be passed directly through the backs of the guides into the window frame.

40 The stop P on the bottom of the shade (see Figs. 11 and 12) comprises a frame 40 with ears 41 and 42 closely enframing the tapering cross section of the shade stick 43. Rivets or screws 44 secure the frame to the 45 stick. Within the frame 40 is rotatably mounted the drum having the helical grooves 46 and 47 extending in opposite directions from the centre. At the centre of the frame is a recess 48. When held in this recess the 50 cord may be drawn through the holder but when released it is quickly moved to one side or the other by a groove in the drum and wedged between the drum and the frame. The holder O on the window sill is 55 of a similar construction except that it is adapted for attachment to the window sill instead of to the shade stick. The shade having a given spread over the surface of the window may be adjusted to any desired part 60 of the window by loosening the cord from the holder O and leaving it secured in the holder P while the spread of the shade may be adjusted without disturbing the position of the shade roller by leaving the cord secured in O and releasing it from P.

Referring to Figures 13 to 17, the channeled bracket guides 49 and 50, the same as the guides F and G of the previous figures, are secured to the outside face of the window frame 51 by means of adjustable sheet metal 70 means. The means for securing the guide 49 comprises a foot 52 secured to the window frame by screws 53 and a flexible or bendable piece or ear 54 riveted to the guide. Similarly the securing means for the guide 75 50 comprises a foot 55 secured to the frame by screws 56 and a bendable piece 57 riveted to the guide. By bending the ears to which they are secured, the guides may be adjusted into alinement or other desired position. At 80 the upper ends of the guides are brackets 58 and 59 carrying the cord guiding pulleys 60 and 61 whence the cords 62 and 63 from the respective shade roller supporting brackets pass to the pulleys 64 and 65 in the frame 85 66 secured to the outer face of the top portion of the window. The cords 62 and 63 then merge into a single cord, passing down the center of the window back of the roller and shade and to cord holders on the window 90 sill and shade stick as described in connection with the apparatus of Figure 1. The adjustable shade roller supporting brackets and shade roller are of the same construction as in Figure 1. 95

While the invention has been illustrated in what are considered its best applications, it may have other embodiments without departing from its spirit and is not therefore limited to the structures shown in the drawings, the appended claims pointing out the invention as required by the patent statutes. 100

What I claim is:—

1. The combination with a window frame, of a shade roller, a shade thereon, brackets supporting the ends of said roller, bracket guides along which the said brackets are movable, secured to said frame, cords secured to said brackets, guides for said cords, an adjustable cord holder on said frame, and an adjustable cord holder secured to the shade, the cord extending from said brackets and over said guides to said cord holder upon the frame and from the cord holder upon the frame to the cord holder upon the shade. 110

2. The combination with a window frame, of a shade roller, a shade thereon, brackets supporting the ends of said roller, said brackets having rotatable wheels, guides for said brackets secured to said window frame, said guides each having grooves adapted to respectively receive opposite sides of a wheel, cords secured to said brackets for adjustably supporting said brackets, cord guides secured to said window frame substantially midway between the aforesaid cord guides, a cord holder secured to the sill of said window frame at substantially the centre thereof, and a cord holder se- 125 130

cured to said shade at substantially its center, the cord extending between the centrally arranged cord guide and the cord holder on the sill, and between the cord 5 holder on the sill and the cord holder on the shade.

3. The combination with a window frame, of a shade roller, a shade thereon, brackets supporting the ends of said roller, said 10 brackets having rotatable wheels, guides for said brackets secured to said window frame, each of said guides having grooves for receiving the opposite sides respectively of a wheel, cords secured to said brackets 15 for adjustably supporting said brackets, cord guides secured to said window frame at the ends of said grooved guides, and cord guides secured to said window frame substantially midway between the aforesaid 20 cord guides.

4. The combination with a window frame, of a shade roller, a shade thereon, bracket guides secured to said frame, brackets receiving the pintles of the shade roller and 25 movable along said guides, each of said brackets comprising a pivoted arm supporting one of the said pintles, the pivotal connection of one of said arms with its bracket being above the axis of the shade roller and 30 the pivotal connection of the other arm with its bracket being below said axis.

5. The combination with a window frame, of a shade roller, a shade thereon, a bracket for supporting one end of said roller, said 35 bracket comprising rotatable wheels, a bracket guide secured to said frame, said bracket guide being channelled to receive said wheels and a cord for adjustably supporting said bracket, the point of attachment of said cord to said bracket and the 40 point of support of the shade roller end by said bracket, being in portions offset in the direction of the plane of said wheels.

6. The combination with a window frame, 45 of a shade roller, a shade thereon, a bracket for supporting one end of said roller, said bracket comprising rotatable wheels, a bracket guide secured to said frame, said bracket guide being channelled to receive said wheels and a cord for adjustably supporting said bracket, the point of attachment of said cord to said bracket and the 50 point of support of the shade roller end by said bracket, being in portions offset in the direction of the plane of said wheels, each of said brackets comprising a pivoted arm supporting a shade roller pindle, the pivotal point of one of said arms with its bracket being above the axis of said roller and the 55 pivotal point of the other of said arms being below the roller axis, the shade roller pindle supported by the arm pivoted below the roller axis being fixed thereto and the other pindle being pivoted to its supporting 60 bracket arm.

7. The combination with a window frame, of a shade roller, a shade thereon, a bracket for supporting one end of said roller, said bracket comprising rotatable wheels, a bracket guide secured to said frame, said 70 bracket guide being channelled to receive said wheels and a cord for adjustably supporting said bracket, the point of attachment of said cord to said bracket and the point of support of the shade roller end by 75 said bracket being in portions offset in the direction of the plane of said wheels, each of said brackets comprising a pivoted arm supporting a shade roller pindle, the pivotal point of one of said arms with its bracket being above the axis of said roller and the pivotal point of the other of said rollers being below the roller axis, the shade roller pindle supported by the arm pivoted below the roller axis being fixed thereto, the other 80 pindle comprising a ball engaging a bracket arm having a channel one end of which forms a socket for said ball, the mouth of the channel being restricted to permit passage of the neck of the pindle, but prevent 85 the passage of the ball, the restricted mouth opening at its upper end into a wider opening to permit the passage of the ball.

8. The combination with a window frame 90 of bracket guides secured to opposite sides of the window, brackets movable along said guides, a shade roller supported by said brackets, one of said brackets having a pivoted roller supporting arm depending from its pivot, and the other of said brackets having a pivoted roller supporting arm which is 95 upstanding from its pivot, cords secured to said brackets at substantially the same distance from the axis of said roller, cord guides at the corners of said frame, and a 100 cord guide secured to the top of said frame at substantially the middle.

9. The combination with a window frame, 105 of a channelled bracket guide, a shade roller supporting bracket entering within said guide and movable along the same and means for securing said guide to said frame comprising a foot for securing to said frame and a bendable connection between said foot and said guide.

10. A shade roller supporting bracket 110 comprising a pivoted arm having a channel therein extending longitudinally of the arm and comprising a bed for a ball at the end of said channel furthest removed from the pivotal point, said channel having a restricted opening or slot permitting the passage of the ball supporting neck, but not the ball, and an enlarged opening between the said 115 ball bed and the said pivotal point for permitting the insertion of the ball into said channel.

11. The combination with a window frame 120 of a shade roller, a shade thereon, brackets supporting the ends thereof, said brackets 125

having rotatable wheels, bracket guides secured to said window frame, each of said guides having grooves for receiving opposite sides of a wheel respectively, one of 5 said brackets having a shade roller supporting arm, said arm being pivoted below the axis of the shade roller, and upstanding from its pivot end to the shade roller pintle, the other of said brackets having a depending 10 roller supporting arm, said depending arm being pivoted above the axis of the shade roller, and being secured to the pintle thereof by a ball and socket joint, cords for

supporting the said brackets, cord guides at the ends of said bracket guides, cord guides 15 secured to the top of said window frame at substantially the middle portion thereof, a cord holder secured to the sill of said window frame at substantially the middle portion thereof and a cord holder secured to the 20 shade at substantially the middle portion thereof.

In testimony whereof I have signed this specification this 19th day of May 1917.

AUSTIN D. BRIXEY.
